UNITED STATES PATENT OFFICE

ROBERT LEE WHEELER, OF PEORIA, ILLINOIS, ASSIGNOR OF ONE-HALF TO
GEORGE E. POPLETT, OF PEORIA, ILLINOIS.

CORNER-SHIELD.

SPECIFICATION forming part of Letters Patent No. 695,184, dated March 11, 1902.

Application filed August 22, 1901. Serial No. 72,916. (No model.)

To all whom it may concern:

Be it known that I, ROBERT LEE WHEELER, a citizen of the United States, residing at Peoria, in the county of Peoria and State of Illinois, have invented a new and useful Corner-Shield, of which the following is a specification.

This invention relates to a corner-shield adapted to be applied to the corners of stairs, rooms or compartments, and hallways; and the object of the same is to provide a simple and effective device for preventing the collection of dirt or other matter within corners and also have the outer or exposed member of the improved device removable at will and capable of being polished or cleaned and afterward reset.

The invention consists in the construction and arrangement of the several parts, which will be more fully hereinafter described and claimed.

In the drawings, Figure 1 is a perspective view of a portion of stairs, showing the improved device applied to the corners thereof. Fig. 2 is a transverse vertical section through a corner structure and the improved device. Fig. 3 is a detail perspective view of the inner locking member of the improved device. Fig. 4 is a detail perspective view of the outer member of the improved device.

Similar numerals of reference are employed to indicate corresponding parts in the several views.

The numeral 1 designates an inner locking member, which is of reduced triangular form and constructed with a central aperture 2 and oppositely-disposed side arms 3 of a resilient nature, the said arms projecting forwardly and having inwardly-extending locking-lips 4 at their front free ends. This inner locking member 1 is of a rigid nature and is secured in place by a screw 5, inserted through the aperture 2 and terminally embedded in a corner structure 6, the corner structure being either a part of stairs, as shown, or room, compartment, or hallway. The threaded extremity of the screw 5 is applied in such manner as to enter the angle of the corner structure, and it will be seen that in view of the triangular shape of the mem-

ber 1 said member will be held in immovable position by the single fastening set forth.

Removably applied over the inner locking member 1 is an outer resilient covering member 7, having a triangular form and concave edges 8, the central portions of the side edges having slots 9 formed therein to receive the outer free ends of the arms 3 of the member 1. The member 7 when applied is pressed inwardly against the corner structure over the member 1, as clearly shown by Fig. 2, and presents a concave surface, and when the said member 7 is so applied the opposite side edges thereof are pressed inwardly far enough to cause the outer ends of the arms 3 to lock in the slots 9, the lips 4 of the said arms springing inwardly over the portions of the said member 7 adjacent to the said slots. By this means the member 7 will be firmly held against accidental detachment; but when it is desired to remove the same the arms 3 are pressed outwardly to release the lips 4 therefrom, and owing to the resilient nature of the member 7 it will spring forwardly, so that it can be readily grasped for cleaning or other purposes. The curved edges 8 permit the member 7 to closely and snugly fit into the corner structure, so that no crevices will exist between the said edges and the bottom and sides of the corner structure, and hence a complete corner-closure will thus be provided to prevent the collection of dirt or other material in the corners covered by the improved devices. Owing to the downward and outward inclination of the member 7 when applied dirt or other matter falling thereon will be directed outwardly and away from the corner structure with material convenience and advantage during sweeping operations.

It is preferred to form the members 1 and 7 of brass or other non-corrosive material, and said members can be plated or otherwise ornamented and will present a neat and pleasing appearance, particularly in stairways.

Though the improved device has been specially devised for use in houses and in connection with woodwork, it will be understood that applications thereof may be made to other corner structures, and the parts composing

the improved device being simple can be manufactured and sold at a small cost.

Having thus described the invention, what is claimed as new is—

- 5 1. A corner-cover comprising a locking member adapted to be secured over a corner structure, and a covering member applied over the locking member and removably held by the latter, the said covering member being of a resilient nature and presenting an outer concave surface when applied, said surface being inclined downwardly and outwardly from the corner structure, the locking member having side arms to removably engage opposite side portions of the covering member.
- 10 2. In a corner-cover, an outer resilient covering member having concave edges, and a locking member having forwardly-projecting arms to engage two of the edges of the said covering member.
- 15 3. In a corner-cover, a locking member, and an outer covering member removably disposed over and engaging portions of the said locking member.

4. A corner-cover having a resilient covering member removably applicable to a corner structure. 25

5. A corner-cover having a covering member removably applicable over a corner structure and adapted to be pressed inwardly into the latter to provide an outer concave surface which is inclined downwardly and outwardly from the said structure. 30

6. In a corner-cover, the combination of a triangular locking-plate adapted to be secured in permanent position and having forwardly-projecting arms at the opposite side edges with outer locking-lips, and an outer covering member of a resilient nature having slots in the opposite side edges to receive the said 35 arms and lips. 40

In testimony that I claim the foregoing as my own I have hereto affixed my signature in the presence of two witnesses.

ROBERT LEE WHEELER.
